UNIVERSAL CLEANERS AND POLISHERS

Peter S. Vosbikian and Thomas S. Vosbikian,
Melrose, Pa.

Application December 20, 1954, Serial No. 476,437

4 Claims. (Cl. 15—118)

The object of our present invention is to devise a novel 15 cleaner and polisher.

A further object of the invention is to devise a novel cleaning and polishing bunch of resilient, absorbing material and maintaining the bunch formation by its attachment to a handle by which it is manipulated.

A further object of the invention is to form the cleaning and polishing bunch of laminations in sheet form and compressing them along their longitudinal axis to cause the portions of the laminations at opposite sides of such longitudinal axis to assume a radial disposition. The compression is preferably made by a U-shaped retainer, the prongs of which when compressed are connected with a handle.

A further object of the invention is to devise a novel cleaner and polisher having a plurality of replaceable heads of sponge material and in which the sponge material of one head has a greater abrading action than that of the other head.

The sponge material may be of any desired character, for example the laminations may be of rubber, rubber composition, cellulose, sponge, plastic or any combination of such components, although we prefer a plastic of cellular construction having fibre-glass incorporated therein with a multiplicity of cells, since we have found that such material provides an effective friction surface.

A further object of the invention is to devise novel means for securing cleaning and polishing heads or bunches to their handle, whereby when a head has been worn it can be removed and replaced by unskilled labor.

With the foregoing and other objects in view as will hereinafter clearly appear, our invention comprehends a novel cleaner and polisher for manual manipulation.

For the purpose of illustrating the invention, we have shown in the accompanying drawings preferred embodiments of it which we have found, in practice, to give satisfactory and reliable results. It is, however, to be understood that the various instrumentalities of which the invention consists can be variously arranged and organized, and the invention is not limited except by the scope of the appended claims to the exact arrangement and organization of these instrumentalities as herein set forth.

Figure 1 is a perspective view of a novel cleaner and polisher, embodying our invention.

Figure 2 is an enlarged perspective view of laminations and their retainer before assemblage.

Figure 3 is an enlarged perspective view showing prongs of the retainer compressing the laminations.

Figure 4 is an enlarged section on line 4—4 of Figure 1.

Figure 5 is an enlarged section on line 5—5 of Figure 1.

Figure 6 is a top plan view.

Figures 7 and 8 are perspective views of another embodiment of the invention with a plurality of cleaning heads.

Figure 9 is a perspective view showing the use in an utensil of the embodiment seen in Figure 8.

2

Figure 10 is a sectional elevation of the implement of Fig. 8.

Figure 11 is a sectional view of a portion of an embodiment.

Figure 12 is a perspective view of a spiral arrangement of the laminations.

Similar numerals of reference indicate corresponding parts in the drawings.

Referring to the drawings:

10 The cleaning and polishing head of the device is made up of any desired number of laminations 1 of sponge material in sheet form assembled together in contact and in registry. The laminations are retained in assembled condition by a U-shaped retainer 2 having spaced prongs 3 and 4 which are spaced to be of less width than that of the assembled laminations. The prongs are spread out and slipped over the assembled laminations as shown in Figure 3, so that they are disposed along the longitudinal axis of the laminations to be equidistant from opposite side edges of the laminations. The loop or curved outer end of the retainer 2 is protected by a piece of sponge or other material 5, and as shown the prongs are passed through the material 5 to be embedded therein so that the loop portion will not come into contact with the article being cleaned. The prongs 3 and 4 after passing beyond the inner ends of the laminations are pressed together towards each other to compress the laminations along their longitudinal axis, and the free ends of the prongs 3 and 4 are driven into an aperture 6 in the end of a handle 7. The inner ends or end portions of the prongs may be flattened so that they will spread out at the inner end of such aperture and provide a tighter fit in such aperture.

20 The laminations are substantially flat, and when the retainer is driven home into the handle, the laminations will assume a radial disposition relatively to the prongs as shown in the drawings. This also causes the outer and inner walls at the ends of the laminations to converge inwardly.

25 30 35 40 This convergence of the outer ends of the laminations forms a substantially cone-shaped outer end which can more readily be inserted into a tumbler, bottle, cup or other open ended container.

45 The cleaner just described can be used in a dry or wet state.

45 In the embodiment seen in Figures 7 to 10, inclusive, we have shown the cleaner and polisher as having a plurality of cleaning heads capable of separate or simultaneous use, and one of these heads, namely the head 8, is of the same construction and arrangement as that already described having the laminations of sponge material secured along their longitudinal axis by a U-shaped retainer 9 compressing the laminations 10. The loop portion of the retainer is protected by a piece of sponge material 11 similar to the protecting material 5 seen in Figures 1 to 6, inclusive.

50 55 60 65 The prongs of the retainer are connected with a body portion 12 in the form of a rod having a clamp 13 to which a handle 14 is pivotally connected by a fastening device 15. This provides for the angular adjustment of the handle relatively to the body portion. The body portion is internally threaded at the ends as at 15 and 16. A nipple 17 is externally threaded to be received by the internal threads 15 and the nipple is apertured to receive the prongs of the retainer as at 18.

65 70 75 The internal threads 16 receive a similar nipple 19 apertured at 20 to receive the prongs of a retainer 21 for securing in place a head 22 of sponge material having a greater abrasive action than the head 8 and formed of metal sponge material in the form of a pad or a coiled strand or strands formed into a cleaning and polishing bunch. An abutment 23 on body portion 12 interlocks

with a block of absorbent sponge material 24 which contacts the rear of the head 22. This provides sufficient moisture for the operation of the metallic sponge material 22.

The nipples may be dispensed with and straight holes formed in the ends of the body portion as shown in the embodiment seen in Figure 11, in which case a staple 25 is driven into a hole 26 in a body portion 27 so that the front ends of the staple are slightly bent at the blind end of the hole, and therefore wedge more tightly in the body portion.

When the nipples are employed the free ends of the prongs of the retainer are bent laterally.

It will now be clear that if a head becomes worn, it can be removed by pulling out the retainer with a pair of pliers as in Figures 1 to 6 and 11, or the nipple can be unscrewed from its body portion and the nipple and the head discarded, and a new head inserted in place. The heads can therefore be replaced by unskilled labor and it is not necessary to return the cleaner and polisher to the factory for such replacement.

As illustrated in Figures 7 and 9 where two heads of contrasting material are employed, both heads are simultaneously used in the cleaning operation, the handle being adjusted to the proper angle for clearing parts of the article to be cleaned.

The head or bunch of laminations will assume a spiral arrangement as shown in Figure 12, if, after the prongs have been driven part way into the handle or body portion, they are given a partial turn and then driven their full way into the handle or body portion.

Having thus described our invention, what we claim as new and desire to secure by Letters Patent is:

1. A cleaner and polisher, comprising elongated laminations of cellular sponge material in flat sheet form assembled together, a U-shaped retainer having prongs extending longitudinally along opposite sides of the central portions of the assembled laminations, and a handle arrangement having an end aperture receiving the ends of said prongs when the latter are pressed together, thereby causing lateral compression of the central portions of the laminations, their radial disposition and circumferential spacing, said prongs extending into said end aperture to an extent to cause the inner central portion of the assembled laminations to be compressed against the handle arrangement and the central portions at the outer ends of the lamination to be compressed towards the handle arrangement, whereby the inner and outer ends of the assembled laminations assume a coned formation to facilitate their entrance into and their removal from a tubular or cup shaped article to be cleaned or polished.

2. A cleaning and polishing device, comprising an elongated body portion having apertures at opposite ends one of which is threaded, a clamp centrally fixed to the body portion, a handle pivoted to said clamp for angular adjustment, a cleaning head having laminations of absorbent material assembled face to face, a U-shaped retainer having spaced prongs compressing the central portions of the laminations, a nipple threaded into said one end and having an aperture, said prongs passing through said nipple aperture and having their ends bent

outwardly against the inner end of the nipple whereby the laminations, retainer and nipple form a unit of structure, and a second cleaning head of greater abrasive characteristics than the first head secured in the other end 5 aperture of the body portion, said body portion providing a short coupling between the heads whereby said heads simultaneously contact a curved surface to be cleaned.

3. A cleaning and polishing device, comprising an elongated body portion having apertures at opposite ends one of which is threaded, a clamp centrally fixed to the body portion, a handle pivoted to said clamp for angular adjustment, a cleaning head having laminations of absorbent material assembled face to face, a U-shaped retainer having prongs compressing the central portion of the laminations, a nipple threaded into said one end aperture and having an aperture in which said prongs are secured whereby the laminations, retainer and nipple form a unit of structure, a second cleaning head having greater abrasive characteristics than said first head having 10 a block of metallic sponge material, a second nipple secured in the aperture at the other end of the body portion, and a U-shaped retainer securing said block of metallic sponge material to said second nipple.

4. A cleaning and polishing device, comprising an elongated body portion having apertures at opposite ends one of which is threaded, a clamp centrally fixed to the body portion, a handle pivoted to said clamp for angular adjustment, a cleaning head having laminations of sponge material assembled face to face, a U-shaped retainer having spaced prongs compressing central portions of the laminations, a nipple threaded into said one end threaded aperture and having an aperture, said prongs being secured in said nipple aperture, whereby said laminations, retainer and nipple form a unit of structure, a second head having a block of metallic sponge material with a backing of sponge material abutting said body portion, a second nipple secured in the aperture at the other end of said body portion, and a retainer securing said block of metallic sponge material 20 and said backing to said second nipple.
